(57) **CLAIM**

The ornamental design for a kitchen aid for forming rolled food products, as shown and described.

DESCRIPTION

FIG. 1 is an isometric view of the design from one end and one side.

FIG. 2 is an end elevational view of the design where the opposite end is not shown but is identical.

FIG. 3 is an isometric view of the design from the bottom and the same side.

FIG. 4 is a side elevational view of the design from one side.

FIG. 5 is a side elevational view of the design from the opposite side.

FIG. 6 is a top plan view of the design; and,

FIG. 7 is a bottom plan view of the design.

The design consists of the shape and arrangement of the design as shown in the Figures.
